AUXILIARY HEATER FOR BROODERS

Perry S. Martin, Harrisonburg, Va.

Application January 14, 1928, Serial No. 246,800

14 Claims. (Cl. 119—31)

This invention relates to brooders, an object of the invention being to provide an auxiliary heating element for operation independent of the usual heating elements under the hover, the 5 same being arranged in a damper controlled air duct formed between a pair of insulated walls formed in rear of the brooder for efficiently increasing room temperature in the brooding room by opening the damper.

10 Another object of the invention is the provision of auxiliary heating elements comprising heating pipes through which hot water is circulated, the pipes extending through air ducts arranged in the rear of brooders in brooding 15 rooms, the same being found very practical in connection with colony brooders having a plurality of brooding rooms through all of which the pipes extend.

10 Another object of the invention is to provide 20 an auxiliary heater in connection with a brooding system in which cool air passes to the brooder through a passageway arranged under the floor of the brooding rooms, said auxiliary heater also receiving air from the passageway and working 25 entirely independent of the system of heat control under the hover and being arranged for increasing entire room temperature.

It is also an object of the invention to provide 30 an auxiliary heater of the above mentioned character, which is simple and substantial in construction, which can be manufactured economically in connection with brooders, and which will be thoroughly efficient and practical in use.

With the foregoing and other objects in view, 35 which will be apparent as the description proceeds, the invention resides in the construction and arrangement of parts, as hereinafter described and claimed, it being understood that changes can be made within the scope of what 40 is claimed, without departing from the spirit of the invention.

The invention is illustrated in the accompanying drawing, wherein:

Figure 1 is a vertical section through a brooder 45 showing my improved auxiliary heater associated therewith,

Figure 2 is a vertical section taken on line 2—2 of Figure 1, and

Figure 3 is a fragmentary section showing a 50 slightly modified form of the invention.

Referring to the drawing, the numeral 10 generally designates either the side walls of a brooder room or the partitions in such a room forming 55 separate units of a brooder of the construction shown in my Patent No. 1,592,377 entitled "Col-

ony brooder", my pending application entitled "Colony brooder", filed January 21, 1927, Serial No. 162,527, and the application Serial Number 246,799, filed of even date entitled "Brooder house", in which are disclosed adjustable hovers 60 carried by a rear wall 12 and having thereunder a plurality of heat radiating pipes 13 about which air is circulated for obtaining hover temperature. The air circulated about the heat radiating pipes 13 passes under the floor 14 of the brooding room through a passageway 15 such as that shown in my application above mentioned 65 entitled "Brooder house". In such application, the cool air passes downwardly and enters the passageway 15 at the forward side of the house 70 and then passes rearwardly and enters the brooding room through an opening 16 in the floor at the rear of the brooding room where the brooder is arranged, said brooder being positioned over 75 the opening so that air passing through the opening 16 passes around the heat radiating pipes 13.

When using brooders and brooding houses of the above mentioned character in northern countries where the climate is very cold and blustery, proper hover temperature is had, but often entire 80 room temperature of the desired degree is a little difficult to obtain. Therefore, I have provided an auxiliary heater for increasing room temperature without affecting hover temperature.

In carrying out the invention, the brooder is 85 positioned in the brooding room a sufficient distance from the rear wall 17 thereof for permitting the placing therebetween of a partition 18, said partition 18 being reinforced at its upper and lower edges by means of strips 19 and 20 respectively which extend across and are attached to the end members of the brooder. As the end members of the brooder have cleats extending down their forward and rearward edges, the strips 19 and 20 as well as the insulating partition 18 90 may be attached to said cleats and abut against the end members. The partition 18 is spaced from the rear wall 12 of the brooder for providing an air duct or passageway 21 which extends 95 downwardly to the floor 14 of the brooding room and is in communication with the passageway 15 under the floor of the brooding room through the opening 16. Across the opening 16 is arranged 100 wire mesh material or the like 22. It can thus be seen that air circulating under the floor 14 through the passageway 15 will not only pass around the heat radiating pipes 13 but will pass 105 upwardly through the air duct or passageway 21. Extending longitudinally of the air duct at the lower portion thereof is a pair of heat radiating 110

5 pipes 23 and 24 around which the air passing up
the air duct 21 must pass. By referring to Figure 1 of the drawing, it can be seen that the pipes
10 23 and 24 are arranged one above the other with
5 the pipe 23 slightly in advance of the pipe 24 so
as to eliminate to a great extent the direct passage of air at either side of both pipes, thus causing
15 to a certain extent the air to wind around the heat radiating pipes. The pipes 23 and 24 are connected
20 with the heater so that the pipe 23 forms a flow pipe and the pipe 24 a return pipe forming circulation from and to the heater.

At the upper end of the air duct or passageway
15 21 hingedly connected to the strip 19 is a damper
25 which may be swung to various adjusted positions so as to regulate the flow of air through the air duct or passageway 21. Attached to the rear wall 12 of the brooder is a rest strip 26 which is engaged by the damper 25 when said damper is
30 in closed position so as to form a stepped seal as well as means for limiting downward movement of the damper 25. The damper 25 has connected thereto a chain or other flexible element 27 which is adapted to be engaged by a hook 28 carried by
35 the rear wall of the brooder house in order to hold the damper 25 in adjusted position. It can be seen that when the damper 25 is open air after passing around the heat radiating pipes 23 and 24 will be permitted to escape from the air duct or passageway 21 and pass into the brooding room for forming an auxiliary means for heating the brooding room.

It is to be noted that the strip 20 which is attached to the lower edge of the partition 18 is spaced slightly above the opening 16 in the floor 14 and that the partition 18 is spaced slightly from the rear wall 17 of the brooding house, which will form an air space communicating with the interior of the room and the passageway 15 for preventing the cold air exteriorly of the building from cooling or otherwise affecting the warm air either in or passing through the air duct or passageway 21.

In Figure 3 of the drawing, the heat radiating
45 50 pipes 23 and 24 are illustrated one directly above the other, but in order to prevent air from passing directly to either side of the heat radiating pipes, baffle strips 29 are attached to the rear wall 12 of the brooder and the strip 20 to which the partition 18 is attached. One of the baffle strips 29 is arranged above and to the forward side of the heat radiating pipes, while the other baffle strip is arranged to the rear and between the two heat radiating pipes, thus providing an obstructed, tortuous passageway through which the air must pass in order to pass upwardly through the air duct or passageway 21, the same serving the same purpose as staggeredly positioning the heating pipes 23 and 24 as shown in the preferred form of my invention.

During ordinary weather conditions, it may not be necessary to use the auxiliary heater in order to provide proper room temperature. In such case, the chain may be released from the hook 28 and the damper 25 closed, and the heat remains confined in the air duct or passageway 21. The auxiliary heater works entirely independent of the temperature under the hover so that the closing of the damper 25 will not affect the hover temperature. When the damper is closed, the heat is held in the passageway or air duct 21 due to the insulated walls of the air duct or passageway and none will escape to the room, due to the tendency of heat to rise. When the damper 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 - opening is in the floor and the part not covered by the brooder is covered by the bottom of an air duct rising from the floor, the air duct and brooder having one wall in common.
- 5 8. In combination, a brooder room, an elongated mesh covered opening traversing one of the interior surfaces parallel to and adjacent an adjoining surface, an elongated brooder partly covering said opening whereby part of the air entering the room passes thru the brooder, means adjacent said opening and within the brooder for heating said air, and heating means adjacent said opening exterior the brooder whereby air entering the room thru the duct formed by said adjoining surface and said brooder is heated as it passes into the room.

9. The device of claim 8 in which the opening is in the floor and the brooder traverses the entire room.

- 20 10. In a brooder house, a room, a heating pipe traversing said room adjacent one wall, a second heating pipe parallel to the first but spaced farther from the wall, a floor opening traversing the room directly below the pipes, a brooder traversing the room and having one of its walls between said pipes whereby part of the air entering the room thru the opening passes thru the brooder and the rest of the air passes upward thru a duct formed by said brooder wall and said one wall, both portions of air being heated by the respective pipes.

11. The device of claim 10 in which means are provided for controlling the flow of air thru said duct.

- 25 12. The combination with a brooding room having an opening in its floor for admitting fresh

air, an upright wall traversing said opening, a brooder within the room, an air duct for leading air from the opening to a point above the brooder, said wall being common to the brooder and to the duct, means in the brooder for heating the air entering the brooder, means in the duct for heating the air entering the room, and means comprising a damper for adjusting the flow of air thru the duct.

- 80 13. A multiple brooder comprising a house, partition walls dividing said house into a number of brooder rooms, a brooder in each room, each room having an air inlet passageway communicating with the interior of the brooder, an air duct arranged in the rear of each brooder and communicating with the air passageway and with the interior of the brooding room, said air duct being formed in part by a wall of the brooder and a wall of the room, at least one wall of each brooder consisting of part of one of the partition walls adjoining said last mentioned room wall, and heating means in said air duct for heating air passing therethru.

- 85 14. In a brooding room, a vertical partition adjacent one wall dividing the room into a brooding chamber and an air inlet passageway, closure means for establishing or breaking communication at will between the chamber and a portion of the passageway, two independent heating means, one in the chamber and the other in said portion of the passageway, and a conduit provided under the floor and an opening provided in the conduit adjacent said heating means for admitting air from outside into both the chamber and the passageway.
